UNITED STATES PATENT OFFICE.

CHARLES COSWELL GROSS AND MILTON KELLY GROSS, OF JACKSBORO, TENNESSEE,
ASSIGNORS OF ONE-FOURTH TO WINSTON BAIRD, OF JACKSBORO, TENNESSEE, AND
ONE-FOURTH TO JOHN G. DUNCAN, OF KNOXVILLE, TENNESSEE.

RAIL-JOINT AND TIE-BAR AND NUT-LOCK.

938,314.

Specification of Letters Patent.

Patented Oct. 26, 1909.

Application filed July 8, 1908, Serial No. 442,498. Renewed September 15, 1909. Serial No. 517,917.

To all whom it may concern:

Be it known that we, CHARLES C. GROSS and MILTON K. Gross, citizens of the United States, residing at Jacksboro, in the county 5 of Campbell and State of Tennessee, have invented new and useful Improvements in Rail-Joints and Tie-Bars and Nut-Locks, of which the following is a specification.

This invention relates to combined rail joints and tie bars, and one of the objects 10 of the invention is to provide a joint having structural features which will overcome the defects of ordinary joints as to noise and jar incident to car wheels passing thereover 15 and loosening the bolts and the parts of the joint itself, thereby obviating damage to the rails and injury to the rolling stock, as well as inconvenience and jar to the traveling public.

20 A further object of the invention is to embody in a rail joint a construction which will so unite the rails as to make them practically continuous and to prevent depression of the joints occurring between the ties by 25 the application to the under part of the contiguous ends of the rails of bracing means adapted to be easily disposed between the ties and readily accessible in the operation 30 of applying the parts to the united rail ends, as well as in the disassociation of the rails.

35 A still further object of the invention is to provide a rail joint with a removable tie bar adapted to serve as a gage in spacing the rails and also provide effective means for preventing the spreading of the rails 40 after the device has been applied.

With these and other objects in view the invention consists in the novel construction and arrangement of parts hereinafter fully 45 described and claimed.

In the accompanying drawings, Figure 1 is a top plan view of the improvement illustrating the same in applied position. Fig. 2 is an enlarged sectional view upon the 50 line 2—2 of Fig. 1. Fig. 3 is an elevation looking from the outer side of the contiguous meeting ends of the rails, illustrating the method of locking the rail connecting bolts. Fig. 4 is a detail perspective view of the bolt locking member.

Referring particularly to the rail connecting members the numeral 1 designates the outer member or splice bar and the numeral 2 the inner member or splice bar. These

members are precisely similar in construction each having a base flange 3 which is horizontally straight, and above the same is a downwardly inclined covering flange 4, integrally rising from the outer edge of the flange 3, the space between the two flanges 5 being of such dimensions as to practically embrace one half of the base flanges 6 of rail sections 6 and 7. Rising from the inner terminal of the flange 4 is a fish or locking plate 8 adapted to extend the full length of 65 the joint. The flanges 8 and the webs of the rail sections 6 and 7 are provided with alining openings adapted for the reception of retaining bolts 9 provided with securing nuts 10. Depending from the base flange 5 70 is an integrally formed brace block or enlargement 11. This block 11 is formed flush with the outer edges of the joint and is adapted to occupy a space equal to the distance between two of the rail ties. The base 75 blocks are provided with alining openings adapted for the reception of bolts 12 having retaining heads 13. The nuts 13 are spaced a suitable distance apart and are positioned upon the splice bar having the nuts 10, and 80 this member of the rail joint is also provided with a nut securing device 14. This device or member 14 comprises a vertical plate having cut away portions adapted for engagement with the nuts 13 and being provided 85 with a swinging catch 15 having fingers 16 adapted to overlie one of the nuts 13 and underlie the opposite nut 13. The member 14 is provided with an offset flange adapted to underlie the nuts 10 and effectively prevent their rotation. The flange portion 17 of the device has its ends upturned to provide fingers 18, and these fingers are adapted to lie adjacent the sides of the outermost nuts 10. By this construction 90 it will be noted that all the nuts employed with the device are effectively retained in locked position.

The member of the rail joint opposite the member provided with the nut locking device 14 is provided with a bracket member 19. This member 19 is provided with a vertical flange 20 having suitable openings adapted to be engaged by the bolt 12 by which the member is retained upon the rail 100 joint. While the bracket member 19 is described as being formed separately from the joint, it is to be understood that the same 105

may be formed integrally therewith should it be desired. The bracket 19 is provided with a centrally arranged cut away portion or channel, and this channel is provided 5 with suitable vertical openings adapted for alignment with similar openings provided upon a tie bar 21 and for the reception of suitable retaining elements 22 by which the bar is secured to the bracket. This bar 21 10 has its outer end provided with an upturned inwardly projecting tongue 23, adapted to engage the base flange of the rail member opposite the rail joint. The tie bar 21 is also provided with a sliding securing 15 clip or member 24 having an inclined lip adapted to engage the inner portion of the base flange of the rail. The clip 24 is provided with a suitable threaded aperture adapted for the reception of a threaded ele- 20 ment 25, by which the clip may be retained in secured position upon the bar 21.

From the above description, taken in connection with the accompanying drawings, it will be noted that a device constructed in 25 accordance with the present invention embodies features which effectively connect the contiguous meeting ends of a pair of rails and prevent the same from sagging as well as securely locking the nuts of the rail 30 joints. The device also presents a substantial track gage whereby the rails may be positioned in proper spaced relation with each other and whereby the rails may be securely retained in said spaced position and 35 the spreading of the rails entirely obviated.

Having thus fully described the invention what is claimed as new is:

1. In a device for the purpose set forth a pair of rail connecting members each comprising base flanges provided with base blocks adapted to ride adjacent to and between the ties of the rails, each of said connecting members being provided with an overlying flange and a vertical flange adapt- 40 ed to engage the webs and base flanges of 45 the rails, one of the connecting members

having a projecting bracket provided with a plurality of spaced openings, a tie bar having one of its ends provided with spaced openings alining with the openings in the 50 bracket, securing elements for the tie bar and the bracket, said tie bar having its opposite extremity provided with an upturned inwardly inclined extension, a slideable clip having an extending lip upon the tie bar, 55 and a securing element for connecting the clip with the bar.

2. The combination with rail sections, of connecting members applied against the opposite sides of said contiguous sections and 60 each having an upwardly projecting fish plate rising from an upwardly inclined covering flange integrally formed with a base flange, a base block projecting downwardly from the base flange, bolts for the base block 65 and the vertical flanges and webs of the rails, nuts for the bolts, a nut locking member comprising a vertical plate having cut away portions engaging the nuts of the base block and having a flanged extension engag- 70 ing the nuts of the vertical flange, said extension being provided with upturned fingers adapted to lie against the sides of the outermost nuts of the vertical flange, a swinging 75 latch pivoted to the vertical plate and adapted to engage the sides of the nuts connecting the base blocks, one of said joint members being provided with a bracket, a tie bar secured to the bracket and having an upturned inwardly inclined extension 80 adapted to engage the base flange of the opposite rail, and a clip having an extending lip and a retaining screw slidably mounted upon the tie bar.

In testimony whereof we affix our signatures in presence of two witnesses.

CHARLES COSWELL GROSS.
MILTON KELLY GROSS.
